WILLIAM JONATHAN NEIDIG, OF MADISON, WISCONSIN, ASSIGNOR, BY MESNE ASSIGNMENTS, TO CHICAGO TITLE AND TRUST COMPANY, TRUSTEE, A-CORPORATION OF ILLINOIS.

TYPE-WRITING MACHINE.

1,087,045.

Specification of Letters Patent. Patented Feb. 10, 1914.

Application filed April 30, 1909. Serial No. 493,198.

To all whom it may concern:

Be it known that I, WILLIAM JONATHAN NEIDIG, a citizen of the United States, residing at Madison, in the county of Dane and State of Wisconsin, have invented a new and useful Improvement in Type-Writing Machines, of which the following is a specification.

My general invention supplies the operator of a typewriting machine with automatic indicating means, called into operation under the novel control of a typewriter part used in the operation of typewriting, whereby without exercising preliminary care he is able to inform himself of the position of his advancing sheet, so that he may know at any time the extent of the matter completed on his sheet, and also the extent of the uncompleted portion of his sheet. It also supplies him with automatic indicating means, called into operation under the novel control of such a typewriter part, for indicating the arrival of the sheet into predetermined line positions through the use of various types of signaling and machine-lock devices.

The embodiments of the invention shown in the drawings employ an operative member that is actuated from a pre-attained starting position through a connection with the sheet-advancing means, more specifically in this case the platen, under the control of a typewriter part as aforesaid. Through the said member the several indicating means are herein shown as called into operation by the platen. The construction of the mechanism as a whole is such that backing-up is automatically permitted from any position without affecting the indicating. The said embodiments within their range automatically re-set upon the usual forward removal of the sheet, whether the sheet is completely printed or not, and thereafter when the new sheet is inserted and printed they automatically enter upon their indicating duties and indicate to the operator by means of indices the respective numbers of the lines, counting from the usual first line printed on the sheet, or as desired, all without preliminary care on his part. They also give him a warning signal by means of bell-trip devices, and lock the printing instrumentalities against use in

printing, either or both, when he has written predetermined numbers of lines, and thereafter release said printing instrumentalities for use on the succeeding sheet, all without preliminary care on his part. They also enable him to write a folio number or similar marking at the head of his sheet without counting it as a first line, without care on his part as respects the counting. They also indicate for him without preliminary care as respects that sheet, by means of indices, the decreasing distance from his current printing point to a predetermined point on the sheet such as the sheet-end, or the predetermined page-end. I believe that none of these functions has heretofore been thus performed in typewriting machines without preliminary care, in the case of each sheet printed, on the part of the operator.

Other novel features and uses are as hereinafter described.

Some of the features of the invention and novel combinations of elements as shown in the drawings and described and claimed herein are intended for sheet-position-indicating uses not necessarily limited as respects the inclusion of control by a typewriter-mechanism part as aforesaid.

In the drawings,—Fig. I is an end elevation of a typewriting machine showing an embodiment of my invention as applied thereto, irrelevant details being omitted. Fig. II is a detail view showing the arrangement of indices on the two index-carriers employed in the same, slightly enlarged as compared with Fig. I. Fig. III is a detail view of said index-carriers, in connection with toothed wheel 5 and its axle, further enlarged, and with one of the carriers shown only in outline. Fig. IV is a sectional view of the same. Fig. V is an end elevation of a modification showing a type-bar key-lever employed as a controlling agent. Fig. VI is an end elevation of a modification showing the line-space lever as so used. Fig. VII is a detail view of portions of Fig. VI.

In the drawings the usual main frame of a typewriting machine is indicated at 41, the transversely movable carriage-frame at 12, the paper-table at 8, the platen-roll 105 for advancing the sheet at 10 mounted

fixedly upon its arbor 13 which is journaled near the ends in the carriage-frame, the paper-sheet in the machine at 45, the line-space lever for advancing the platen and through it the sheet at 51, the type-key levers at 58 connected with usual type-carrying parts not shown herein, the type-keys at 59, the space-key levers at 38, and the space-keys at 39. The said usual type-writer-mechanism parts are old; they are or may be of any approved type, as in practice.

The embodiments of the invention illustrated in the several figures employ an operative member that is rotary and which for convenience is mounted to revolve about a different axis from that of the platen. As specifically shown herein the said member has a toothed connection with the platen, but is disconnectible therefrom, and tends to return into initial position when released from the control of the platen through the action of an eccentrically mounted weight thereon. The invention in its broader aspects however is not limited to the employment of a particular type of driving means, nor to the employment of a particular type of means for giving the member its initial position.

Referring to the embodiment shown in Figs. I to IV,--Platen arbor 13 has fixedly attached thereon, as by means of a key, a toothed driver wheel 11. Mounted on carriage-frame 12 as by means of screws 14 is frame-extension 22, bearing pin 9, upon which is journaled hood-piece 31. Said hood-piece serves to support the ends of arbor 21 journaled in the side walls thereof. Arbor 21 bears mounted thereon side by side the toothed wheel 5, index-carrier 6^a and index-carrier 6^b, the said mounted parts being angularly adjustable as will be explained but operating as a unit. Wheel 5 is adapted to mesh with wheel 11 in one position of the hood-piece, but the center of gravity of the hood-piece and its supported parts is well to the right of its axis at 9, and wheel 5 tends to be held out of mesh with wheel 11 by the weight of the said parts. Said wheels may therefore be described as normally out of mesh. Index-carrier 6^a previously referred to is supplied with the eccentrically disposed weight 25, which acts rotatively upon said carrier, except when wheels 5 and 11 are in mesh, to bring the carrier always into a constant position with the same portion of its periphery adjacent to pointer 18 on the hood. This position may be termed its initial or starting position. Wheel 5 aforesaid bears a projection 20 pivoted upon pin 23 and held in working position by stoppin 24. That is to say, the projection is adapted to act operatively upon co-operating parts in the path thereof when operated forwardly against them, but to give way

when operated backwardly against them. The purpose of the provision is to supply a safeguard in addition to the general construction to insure unobstructed backward operation of the mechanism however used.

Hood-piece 31 carries pin 40 bearing bell 27, and it also carries pin 29 upon which is journaled trip-lever 28 having bell-hammer 26 attached thereon. One end of said trip-lever is turned in at right angles toward the carriage-frame, a slot 30 in the hood-piece permitting the turned end of the said trip-lever to project past the hood-piece into the path of projection 20 aforesaid. Frame extension 22 bears also a pin 7, on which is journaled elbow-lever 1 whose upper arm 19 extends into the path of projection 20 aforesaid. The lower arm of said elbow-lever bears a roller or cam-follower 4, adapted to co-operate with a cam-face 15 on the lower part of hood-piece 31 aforesaid. Said cam elements act when in the position shown in Fig. 1 to maintain the hood-piece in its position farthest toward the platen arbor with toothed wheel 5 in mesh with its driver 11, but when roller or cam-follower 4 is raised past the swell of the cam, hood-piece 31 is permitted thereby to rock away from the platen arbor and toothed wheel 5 passes out of mesh with its driver 11. The lower arm of elbow-lever 1 also supports one end of bail-bar 3, which extends parallel with the platen axis from one end of the platen to the other and is supported at the latter end by parts corresponding to said lower arm of lever 1, pin 7, and extension 22. Wearing loosely upon this bail-bar is rod 2, the arrangement being such that the bail-bar is movable transversely with respect to the rod without affecting the position of the rod but when it is moved about its axis at 7 the position of the rod is affected. That is to say, the parts constitute a universal connection between operating elements on the carriage and indicating elements on the main frame, as will be hereinafter described, by means of which the said indicating elements are operated from said operating elements in every position of the carriage, irrespective of the lateral movement of the carriage. The lower end of rod 2 is adjustably attached into the wooden cross-bar 36 by means of nuts 33, at a point about central of the cross-bar. Attached at the ends of cross-bar 36 as by means of screws 34 are the slotted rack-pieces 35, each of which is supplied with a toothed rack 46 adapted to mesh with a toothed segment 47 on arbor 48 journaled at the ends in main frame 41. The central portion of said arbor 48 constitutes lock-bar 50, so shaped that when it sustains a position more or less vertical the type-key levers 58 cannot be depressed, but are locked, but when it sustains a position at

a greater or less angle to the vertical said levers can be depressed as usual, or are released; but the lock-bar is preferably made sufficiently short not to engage space-key levers 38 so as not to lock them. In order that the locking action may be more positive and be effected by a greater range of movement of the lock-bar, I construct said bar with its locking edge turned over to form an arc, and 5

10 I construct the type-key levers with a recess as at 61 into which said lock-bar may pass when in the position occupied before locking. Each of the usual two space-key levers 38 bears a pin 37 which works in the slot 49 in the corresponding slotted rack-piece 35 15 before mentioned.

In Fig. I the mechanism is shown in about the position it would assume shortly before the predetermined time to remove the sheet. 20 An additional rotative movement forward of the platen from the position shown will through toothed wheels 11 and 5 cause projection 20 to act against the turned-in portion 32 of trip-lever 28, hammer 26 will be 25 raised and then released, and the bell 27 will be struck a blow against its edge from within. The operator will thereby be informed that his next line (say) is his predetermined last line. Upon the completion 30 of that line an additional advance of the platen will cause projection 20 to act upon end 19 of elbow-lever 1 and move it a short distance toward the platen-arbor, thereby raising bail-bar 3, rod 2, and cross-bar 36, 35 and through racks 46 and toothed segments 47 rocking lock-bar 50 into locking position under key-levers 58. The printing instrumentalities are now rendered inoperative for use. Ordinarily the platen will now be 40 turned forwardly by the operator in usual manner to remove the sheet. This forward rotation of the platen will cause projection 20 to move lever-end 19 further toward the platen-arbor, cam-follower 4 will thereby be 45 raised further along the cam-face 15 of hood-piece 31 and past the swell of the cam, and the hood-piece will rock by gravity about its axis away from the platen-arbor following the support of the cam-follower aforesaid, bearing toothed wheel 5 out of mesh with toothed driver 11. The moment these toothed wheels become disengaged, weight 25 is rendered effective to rotate carrier 6^a and connected parts so as to bring the 50 carrier to rest always with the same point on its periphery opposite pointer 18, as will always occur when said weight finds its center of gravity. This peripheral point may be supplied with the index 1. The said 55 forward turning movement of the platen that results in the re-setting of the index-carrier as described into initial position, results also in the releasing of the locked printing mechanism, the additional movement of lever 1, bail-bar 3, rod 2 and rack- 60

pieces 35 under the actuation of projection 20 acting through racks 46 and segments 47 to rock lock-bar 50 into a non-locking position past the vertical.

It will be seen that both the resetting and lock-releasing actions described as resulting from the usual forward turning of the platen will occur when the sheet is thus removed, irrespective of the stage of the printing, so that the automatic action of the mechanism will not be affected by the removal of a sheet containing a shorter than the predetermined page. In the said position the parts ordinarily remain until a new sheet is inserted and advanced into 80 printing position. The operator may first, as is often desirable, begin his sheet by numbering it. If so, his operation of the type-keys 59 will leave the indicating mechanism undisturbed, and it will not be affected by the succeeding advance of the sheet into the desired position for printing the first body line. During the printing of the first word of said first body line the parts will still remain undisturbed; but between the first word and the second the operator will use the space-key 39 in ordinary manner, space-key levers 38 are depressed, pins 37 thereon act upon slotted rack-pieces 35 to lower them, and through cross-piece 36, rod 2, bail-bar 3 and elbow-lever 1 swing cam-roller 4 downward along cam-face 15 of the hood-piece, causing the hood-piece to rock toward the platen arbor and bringing toothed wheel 5 into mesh with toothed wheel 11. Upon completing his first line, the operator will rotate the platen sufficiently to advance the sheet into position for receiving the second line. Index-carrier 6^a, now connected to rotate in unison with the platen, will by this action be rotated so that a new portion thereof is brought into indicating position. This portion may be supplied with an index 2 to indicate that the sheet is in position to receive the second line, and the third-line position of the sheet can be indicated by means of an index 3 on the carrier likewise, and so on to the end of the sheet, or as far as may be desired. That is to say, the indicating mechanism 110 more particularly illustrated in Figs. I to IV is controlled by or from the key-levers, or more specifically the space-key levers; or more broadly considered, the indicating mechanism is controlled by or from a typewriter-mechanism part used in the type-writing operation, the invention being not considered by me to be limited as regards the precise typewriter-mechanism part employed for the purpose.

For the purpose of supplying an adjustment provision by means of which the bell-striking and machine-lock devices can be caused to act at any predetermined time or line-position, projection 20 and weight 25 120

are caused to be relatively adjustable angularly as follows: Wheel 5 bearing said projection is provided with a frictional split spring hub 17 over which carrier 6^a bearing 5 said weight may be pressed and by means of which said carrier is held more or less tightly against said wheel. A guide-point 44 projecting from the rim of said wheel so as to coöperate with the indices on the carrier 10 assists the operator in making the desired adjustment. If, for example, the machine is intended to be locked after the printing of thirty-five lines, carrier 6^a is pressed over split spring hub 17 in such 15 angular position that index 35 thereon is in position opposite said guide-point, as in Fig. III. The bell will now sound (say) upon the advance of the sheet into position for receiving the thirty-fifth line, and the machine will be locked after its completion, upon the succeeding advance of the sheet.

I show in my drawings, Figs. II, III and IV, a second index-carrier 6^b, marked to count progressively downward instead of upward the lines upon the sheet being printed. In the case of a page of a predetermined length of (say) thirty-eight lines, said carrier would be adjusted relatively to carrier 6^a until index 38 on carrier 6^b was in 20 position opposite index 1 on carrier 6^a, as in Fig. II, spring hub 17 thereafter acting to hold the parts united so that they will rotate in unison. During the time that carrier 6^a is counting ascendingly from (say) 25 the first line position on the sheet, carrier 6^b will now be counting descendingly, enabling the operator to tell at a glance just how much printing space remains for use in the predetermined page-length. Carrier 6^b 30 can be adjusted to indicate the distance to other points on the sheet, if desired, such as the bottom edge thereof.

Split spring hub 17 that is used to bind wheel 5 and carriers 6^a and 6^b together, but 45 in adjustable relationship, consists of two or more spring tongues attached upon said toothed wheel adjacent to the axle thereof. Said tongues are each given a reverse curve as shown, so that friction-surfaces 16 of the 50 respective carriers may bear upon the tongues in the one case exteriorly and in the other interiorly. Such construction permits the carriers to be readily adjusted or replaced. The carriers shown are inexpensive and easily removed; I propose to use 55 in practice a set of interchangeable carriers bearing indices suitable for use with the different line-spacings, or when desired counting by units other than the line-unit.

60 It is to be noted that the employment of an adjusting means is not essential in the carrying out of the invention, nor if such adjusting means are employed is the character of the same essential. It is to be noted also that in practice I propose to em-

ploy at times any one of the several types of indicating means described, and not the others, or any two or three instead of all.

In the embodiment illustrated in Fig. V the action of the mechanism is the same as 70 has been described, except that the use of a type-key lever through the action thereof upon the underlying cross-bar 52, instead of the space-key lever, calls the previously re-set operative member into action.

In the embodiment illustrated in Figs. VI and VII, the action of the mechanism is likewise substantially the same, except that the use of the line-space lever 51, as in advancing the sheet after the printing of the 80 first line, is availed of to call the previously re-set operative member into action, instead of that of the space-key lever, and the locking arrangement is slightly modified in form. An arm 53 of said line-space lever 85 engages upon lever 54 and rocks said lever, which is journaled upon pin 56 on the carriage-frame, thereby through link 55 and pin 57 on hood-piece 31 rocking said hood-piece toward the platen-arbor and rendering 90 the driving means effective to operate the operative member. Cam-roller 4 follows cam 15 by its own gravity and that of the attached parts, thereby holding the toothed wheels in engagement.

To simplify the drawings, in the case of 95 Figs. V and VI the bell-devices are omitted. It is to be understood, however, that usually in practice bell-devices will be employed.

The term "typewriting operation" as 100 used herein is intended to signify not only the printing but other portions of the general operation of typewriting, including the use of the various parts and attachments at the command of the operator for facilitating 105 his work,—that is to say, including the use of the various "typewriter parts" of a typewriting machine.

The devices shown in the drawings and 110 described herein are part of a series of closely related inventions or improvements which are presented in a number of co-pending applications for Letters Patent filed by me. Certain of the features of the embodiment illustrated in Figs. VI and VII are not 115 specifically claimed herein, but are made more especially the subject of specific claim in my related application filed December 17, 1909, Serial No. 533,725.

I claim as my invention,—

1. In a typewriting machine, in combination, typewriter parts used in the typewriting operation, including sheet - advancing means; an operative member; indicating means called into operation through said 125 member; means for actuating said member from said sheet-advancing means; and means under the control of a typewriter part aforesaid for controlling said actuation.

2. In a typewriting machine, in combina- 130

- tion, typewriter parts used in the typewriting operation, including sheet - advancing means; an index-carrier; means for actuating said carrier from said sheet - advancing means to bring indices into indicating position; and means under the control of a typewriter part aforesaid for controlling said actuation.
3. In a typewriting machine, in combination, typewriter parts used in the typewriting operation, including sheet - advancing means; an operative member; an audible signaling means called into operation through said member; means for actuating said member from said sheet - advancing means; and means under the control of a typewriter part aforesaid for controlling said actuation.
4. In a typewriting machine, in combination, typewriter parts used in the typewriting operation, including sheet - advancing means; an operative member; means called into operation through said member for rendering one or more of said typewriter parts inoperative for use; means for actuating said member from said sheet - advancing means; and means under the control of a typewriter part aforesaid for controlling said actuation.
5. In a typewriting machine, in combination, a platen, an operative member, indicating means called into operation through said member, means for giving said member a constant starting position, a controlling part having also a function in the typewriting operation, and connecting means between said operative member and the platen for giving said member movement from the said starting position, under the control of the said controlling part.
6. In a typewriting machine, in combination, a platen, an index-carrier bearing indices, means for giving said carrier a constant starting position, a controlling part having also a function in the typewriting operation, and connecting means between said carrier and the platen for giving said carrier movement from the said starting position, under the control of the said controlling part.
7. In a typewriting machine, in combination, the main frame; operated typewriter parts, including a carriage, sheet - advancing means, and printing instrumentalities; an operative member on said carriage actuated from said sheet - advancing means under the control of one of said typewriter parts; locking devices on said main frame for locking said printing instrumentalities against use; and means including a universal connection through which said locking devices are called into operation by said operative member in every working position of the carriage.
8. In a typewriting machine, in combination, a platen, an operative member, indicating means called into operation through said member, a controlling part having also a function in the typewriting operation, and toothed devices under the control of said controlling part for giving said member movement from the platen.
9. In a typewriting machine, in combination, typewriter parts including a platen, a revolute member, indicating means called into operation through said member, co-operating toothed wheels one thereof rotating in unison with the platen and one thereof rotating in unison with said revolute member, and means under the control of a typewriter part used in the typewriting operation for controlling the engagement of said toothed wheels.
10. In a typewriting machine, in combination, a platen, an operative member, indicating means called into operation through said member, a controlling part having also a function in the typewriting operation, and connecting devices between said operative member and the platen, said devices normally disengaged and constructed to be engaged through the action thereon of said controlling part.
11. In a typewriting machine, in combination, a platen, an operative member, toothed wheels one thereof moving in unison with the platen and one thereof moving in unison with said operative member, said wheels normally disengaged, means operating to give said operative member a constant starting position upon the disengaging of said wheels, means for causing said wheels to engage so as to give said member movement with the platen from the said starting position, and indicating means called into operation through the said movement of the operative member.
12. In a typewriting machine, in combination, a platen, an operative member, indicating means called into operation through said member, co-operating wheels between said member and the platen, means acting to move and hold said wheels out of mesh, a controlling part having also a function in the typewriting operation, and means controlled by the said controlling part for causing said wheels to pass into mesh from their disengaged position so as to give said operative member movement with the platen.
13. In a typewriting machine, in combination, a platen, an operative member having a projection in connection therewith, indicating means called into operation through said member, co-operating toothed wheels one thereof moving in unison with the platen and one thereof moving in unison with said operative member, means in connection with the projection aforesaid for causing said toothed wheels to disengage, means rendered operative by the disengaging of said toothed wheels for giving said

- operative member a constant starting position, and means acting to engage said toothed wheels at the predetermined time and give said member movement with the 5 platen from the said starting position.
14. In a typewriting machine, in combination, a platen, an operative member having a projection in connection therewith, indicating means called into operation through 10 said member, a controlling part having also a function in the typewriting operation, toothed gearing between said operative member and the platen called into engagement by the operation of said controlling part, 15 means acting in connection with the projection aforesaid to disengage said toothed gearing, and means rendered operative by the disengaging of said gearing for giving said member a constant starting position.
15. In a typewriting machine, in combination, typewriter parts including sheet-advancing means, an operative member, indicating means called into operation through 20 said member, connecting devices for operating said member from said sheet-advancing means, means under the control of said connecting devices for giving said member a constant starting position, and cam devices acting under the control of a typewriter part 25 to control the engagement of said connecting devices.
16. In a typewriting machine, in combination, sheet-advancing means, an operative member actuated from said means, indicating 30 means called into operation through said member, means including cam devices for controlling said actuation, and means under the control of said cam devices for giving said member a constant starting position.
17. In a typewriting machine, in combination, a platen, an operative member, indicating means called into operation through said member, toothed gearing between said member and the platen, and means including 35 cam devices for controlling the engagement of said toothed gearing.
18. In a typewriting machine, in combination, a platen, an operative member, indicating means called into operation through said 40 member, toothed gearing between said member and the platen, a typewriter part, and cam devices under the control of said typewriter part for controlling the operation of said member by said toothed gearing.
19. In a typewriting machine, in combination, sheet-advancing devices, a key-lever used in the typewriting operation, an operative member actuated from said sheet-advancing devices under the control of said 45 key-lever as so used, and indicating means called into operation through said member.
20. In a typewriting machine, in combination, sheet-advancing means, an operative member, indices called into operation 50 through said member, means connecting said member to be actuated from said sheet-advancing means, and a key-lever used in the typewriting operation, said key-lever connected to control said actuation.
21. In a typewriting machine, in combination, sheet-advancing means, an operative member, an audible signaling means called into operation through said member, means connecting said member to be actuated from said sheet-advancing means, and a key-lever used in the typewriting operation, said key-lever connected to control said actuation. 70
22. In a typewriting machine, in combination, typewriter parts including sheet-advancing means and a key-lever, an operative member, means called into operation through said member for rendering certain of the typewriter parts inoperative for use, and means connecting said operative member to be actuated from said sheet-advancing 75 means under the control of said key-lever as used in the typewriting operation.
23. In a typewriting machine, in combination, sheet-advancing means, an operative member, indicating means called into operation through said member, means connecting said member to be actuated from said sheet-advancing means, and a space-key lever connected to control said actuation. 80
24. In a typewriting machine, in combination, a platen, a space-key lever, an operative member, indicating means called into operation through said member, a weight adapted to act rotatively on said member to return the same into initial position, and toothed gearing connectible under the control of said space-key lever for giving said member movement with the platen from the 90 said initial position.
25. In a typewriting machine, in combination, sheet-advancing means including a platen, an operative member, indicating means called into operation through said member, means rendered operative by the forward movement of the platen for giving 100 said member a constant starting position, and means for actuating said member from said starting position at the predetermined time, including connecting means between the member and said sheet-advancing means. 110
26. In a typewriting machine, in combination, sheet-advancing means including a platen, an index-carrier bearing indices, means rendered operative by the forward movement of the platen for giving said carrier a constant starting position, and means for actuating said carrier from said starting position at the predetermined time, including connecting means between the carrier and said sheet-advancing means. 120
27. In a typewriting machine, in combination, a platen, an operative member, indicating means called into operation through said member, means rendered operative by the forward movement of the platen for 130

giving said member a constant starting position, a controlling part having also a function in the typewriting operation, and means for giving said operative member 5 movement correlated with that of the platen from the said starting position, under the control of said controlling part.

28. In a typewriting machine, in combination, a platen, an operative member, indices called into operation through said member, means rendered operative by the forward movement of the platen for resetting said member in initial position, a controlling part having also a function in the 15 typewriting operation, and means for giving said operative member movement correlated with that of the platen from the said initial position, under the control of said controlling part.

29. In a typewriting machine, in combination, a platen, an operative member, indicating means called into operation through said member, means rendered operative by the forward movement of the 25 platen for giving said member a constant starting position, toothed gearing between said member and the platen for giving said member movement with the platen from the said starting position, and means for controlling the engagement of said toothed gearing.

30. In a typewriting machine, in combination, a platen, an operative member actuated from the platen, indicating means 35 called into operation through said member, and a controlling part having also a function in the typewriting operation connected to control the actuation of said operative

member, said mechanism constructed to permit backing-up from any working position. 40

31. In a typewriting machine, in combination, a platen, an operative member, indicating means called into operation through said member, coöperating toothed wheels between said member and the platen, and a 45 controlling part having also a function in the typewriting operation connected to control the engagement of said wheels, said mechanism constructed to permit automatic backing-up from any position. 50

32. In a typewriting machine, in combination, a platen, an index-carrier supplied with indices, coöperating toothed wheels between said carrier and the platen, and a controlling part having also a function in the 55 typewriting operation connected to control the engagement of said wheels, said mechanism constructed to permit automatic backing-up from any position.

33. In a typewriting machine, in combination, typewriter parts including printing instrumentalities and sheet-advancing means, an operative member actuated from said sheet-advancing means under the control of a typewriter part, and devices called 60 into operation through said operative member for locking said printing instrumentalities against use, said locking devices constructed to release automatically for further printing upon the usual forward removal 70 of the sheet.

WILLIAM JONATHAN NEIDIG.
